LLP

(57) **CLAIM**

The ornamental design for crimping pliers, as shown and
described.

DESCRIPTION

FIG. 1 is a perspective view of crimping pliers, showing our
new design;

FIG. 2 is a left side view of the crimping pliers of FIG. 1;
FIG. 3 is a right side view of the crimping pliers of FIG. 1;
FIG. 4 is a front view of the crimping pliers of FIG. 1;
FIG. 5 is a rear view of the crimping pliers of FIG. 1;
FIG. 6 is a top view of the crimping pliers of FIG. 1;
FIG. 7 is a bottom view of the crimping pliers of FIG. 1;
FIG. 8 is a perspective view of another embodiment of the
crimping pliers of FIG. 1;
FIG. 9 is a left side view of the crimping pliers of FIG. 8;
FIG. 10 is a right side view of the crimping pliers of FIG. 8;
FIG. 11 is a front view of the crimping pliers of FIG. 8;
FIG. 12 is a rear view of the crimping pliers of FIG. 8;
FIG. 13 is a top view of the crimping pliers of FIG. 8; and,
FIG. 14 is a bottom view of the crimping pliers of FIG. 8.
The broken lines shown in the drawings illustrate portions of
the crimping pliers that form no part of the claimed design.

1 Claim, 8 Drawing Sheets
